TERMINAL CONNECTOR FOR ELECTRICAL CONDUCTORS

William J. Larkin, Lynnfield, Mass., assignor to National Company, Inc., Malden, Mass., a corporation of Massachusetts

Application March 7, 1946, Serial No. 652,650

5 Claims. (Cl. 173—269)

1

This invention relates to a terminal for securing an electric conductor to a contact and finds a particular application in making a connection to the projecting prong contacts of electronic tubes, more particularly those which extend axially from the end of the tube.

In the present-day development of electronic mechanism tubes of small size are increasingly used. The complexity and the required exactitude of construction of the electrical systems of which they form a part tend to increase. Such systems also are frequently used in situations where they are subject to mechanical shocks and displacements. All these facts have rendered many types of terminal previously used unsatisfactory. The object of the invention is to provide a construction which will meet the demands of present day use, as just referred to, as will be apparent to those skilled in the art as the description proceeds.

My invention will be well understood by reference to the following description taken in connection with the accompanying drawings, wherein:

Fig. 1 is a side elevation of a tube of the so-called acorn type having a prong contact extending from its upper end to which a connection is made (herein to a conducting wire) by a terminal illustrative of the invention;

Fig. 2 is an enlarged view of one side of the terminal as seen in Fig. 1;

Fig. 3 is a view of the other side;

Fig. 4 is a section on the line 4—4 of Fig. 2; and Fig. 5 is a section on the line 5—5 of Fig. 4.

I believe that the invention will be best understood by first describing the exact mechanical construction shown as the principles exemplified thereby and the functions subserved can then be readily understood. In Fig. 1 of the drawings I have shown an electronic tube *t* of the so-called acorn type mounted in a socket *s* having contacts *c* which receive prongs extending radially from the side wall of the tube. A prong *p* extends from the upper end of the tube and to this a connection is made, in the example illustrated from a conducting wire *w*, by means of a terminal illustrative of the invention.

Referring now to Figs. 2 through 5, the terminal shown comprises an elongated strip or thin ribbon *10* of soft flexible metal, as soft copper. While the dimensions may vary, it may be helpful to say that the drawing represents a commercial device in which the strip is about 1 inch long and $\frac{1}{8}$ of an inch wide exclusive of the ears *16* herein-after to be referred to, and about $\frac{1}{100}$ of an inch thick. It is here shown twisted through an angle *58*

2

of 180° in its length. To one end, that at the right in Fig. 1, at a point radially remote from the contact prong *p* connection is made to some other element of the system of which the tube forms a part. This connection is herein diagrammatically illustrated by the showing of a conducting wire *w* soldered to the end of the strip.

Mounted at the other end of the strip, that at the left in the drawing, is a gripping element *12* which is made of relatively hard and brittle and more resilient metal, such as a suitable alloy of copper and beryllium. Herein the element *12* has a part *14* mounted on one face of the strip *10* and herein shown as held thereagainst by integral ears *16* projecting from the longitudinal edges of the strip *10* and bent over the part *14*. The end of this part may have an upturned lug *18* forming a projection interlocking with the ears *16* and preventing withdrawal of the element *12* toward the left in the figures. The piece *12* is bent across the end of the strip *10* and rebent to provide a resilient jaw *20* overhanging and opposing the other face of the strip *10* and this jaw may be provided with a groove *22* to receive the prong *p* when it is thrust beneath the jaw between the same and the opposing face of the strip *10* in a direction transverse to the length of the latter. The ends of the groove may be slightly flared as best seen in Fig. 5 to facilitate entrance of the prong.

A strip of soft copper especially when of such thinness as to provide a freely flexible ribbon-like connector bent to form would not have sufficient resilience to make and maintain an adequate contact with the prong. On the other hand, an elongated member made of such resilient material as beryllium copper would be objectionably brittle and likely to be fractured either in the assembly of the electronic mechanism or during the use thereof. Herein, however, the piece *12* serves to press the prong *p* into firm contact with the opposed face of the soft copper strip *10* which is the main conducting element of the terminal and the piece *12* itself is subject to little or no mechanical strain other than its resilient tension. The soft copper strip *10* extends laterally from the tube for a considerable distance before being electrically connected to some other element of the electronic system, as is desirable for electrical reasons. It may be freely bent or twisted as the necessity or convenience of making the desired connection may dictate in a manner which would be impossible were it hard and resilient. The 180° twist illustrated is an example of such a deformation. It is also well adapted to resist

shocks arising during the use of the system of which it forms a part. The construction is simple, easy and inexpensive to manufacture.

I am aware that the invention may be embodied in other specific forms without departing from the spirit or essential attributes thereof, and I therefore desire the present embodiment to be considered in all respects as illustrative and not restrictive, as is in fact clear in several matters from the description itself. Reference is to be had to the appended claims to indicate those principles of the invention exemplified by the particular embodiment described and which I desire to secure by Letters Patent.

I claim:

1. A terminal connector for an electrical conductor for making connection to a rod-like contact comprising an elongated ribbon of soft flexible metal, a relatively short piece of relatively hard resilient metal secured to one face of an end of the ribbon, leaving the greater portion of the ribbon as a freely flexible, low resistance conductor for extension to and connection at a remote point, said piece being recurved over the ribbon to provide a resilient arm opposing the other face between which arm and the other face the contact may be inserted to be powerfully pressed into direct contact with the ribbon.

2. A terminal connector for an electrical conductor for making connection to a rod-like contact comprising an elongated ribbon of soft flexible metal, a relatively short piece of relatively hard resilient metal having a part overlying one face of an end of the ribbon, leaving the greater portion of the ribbon as a freely flexible, low resistance conductor for extension to and connection at a remote point, said part being mechanically interlocked with the end of the ribbon and being recurved over the other face thereof to provide a resilient arm opposing the other face between which arm and the other face the contact may be inserted to be powerfully pressed into direct contact with the ribbon.

3. A terminal connector for an electrical conductor for making connection to a rod-like contact comprising an elongated ribbon of soft flexible metal, a piece of relatively hard resilient metal having a part overlying one face of an end of the ribbon, leaving the greater portion

of the ribbon as a freely flexible, low resistance conductor for extension to and connection at a remote point the ribbon having marginal ears bent over said part to secure it, the part having a projection to interlock the ears, the piece being recurved over the ribbon to provide a resilient arm opposing the other face between which arm and the other face the contact may be inserted to be powerfully pressed into direct contact with the ribbon.

4. A terminal connector for an electrical conductor for making contact with a rod-like contact comprising a spring of resilient metal defining a pair of opposed gripping jaws and a facing of relatively soft metal at the inner face of one only of the jaws, said facing being integrally extended as a relatively long ribbon-like conductor for extension to and connection at a remote point.

5. A terminal connector for an electrical conductor for making connection to a rod-like contact comprising an elongated ribbon of flexible metal and a short spring of relatively resilient metal mounted on one face thereof adjacent an end, the spring having opposed, relatively yieldable arms to the inner face of one of which an end portion of the ribbon is secured, leaving the greater portion of the ribbon as a freely flexible, low resistance conductor for extension to and connection at a remote point, the contact being insertable between said end portion of the ribbon and the second arm to be powerfully grasped by the resilient arm and pressed by the resilient reaction into direct contact with the end portion of the ribbon which is supported by the first arm.

WILLIAM J. LARKIN.
